MIRROR

Bernard P. Donnelly, Holland, Mich., assignor to Donnelly-Kelley Glass Company, Holland, Mich., a corporation of Michigan

Application July 10, 1958, Serial No. 51,729

Term of patent 14 years

(Cl. D25—1)

The figure is a front elevational view of a mirror of conventional thickness, showing my new design.

I claim:

The ornamental design for a mirror, substantially as shown and described.
